(57) **CLAIM**

The ornamental design for a consumable shape, as shown and described.

DESCRIPTION

FIG. 1 is a front, top, right perspective view of a consumable shape in accordance with our new design;
 FIG. 2 is a rear, bottom, left perspective view thereof;
 FIG. 3 is a front elevation view thereof;
 FIG. 4 is a rear elevation view thereof;
 FIG. 5 is a top plan view thereof;
 FIG. 6 is a bottom plan view thereof;
 FIG. 7 is a left elevation view thereof;
 FIG. 8 is a right elevation view thereof; and,
 FIG. 9 cross-sectionally illustrates exterior surfaces through line 9-9 in FIG. 3.

The broken lines shown in the FIGs. illustrate portions of the consumable shape that form no part of the claimed design.
